TOOL HOLDER ADAPTED FOR MOTOR DRIVEN STRIKING TOOLS

Application filed February 16, 1931, Serial No. 516,110, and in Sweden February 6, 1930.

The present invention relates to an arrangement in tool holders adapted for motor-driven striking tools, in which the very working tool, for instance a borer, a punch or the like, is inserted into the holder. In such holders it easily happens that the tool, for instance the borer, is thrown out away from the holder when the fore end of the borer comes out at the opposite side of the wall or the like to be pierced.

According to the present invention this inconvenience is avoided by the fact that a portion of the tool-holder is made of a resilient matter, for instance rubber, and that a channel arranged in this portion in order to allow the tool to be pushed into the holder, is given a cross-section similar to, but less than the cross-section of the tool shaft. When the tool is pressed into the holder, that portion 20 of the holder which is made of resilient matter will, thus, entirely by its own elasticity press against the tool shaft and hold or lock this by friction.

The annexed drawings show an embodiment of the invention, applied to a holder for locking a borer having a shaft cross-shaped in section.

Fig. 1 shows the striking tool as a whole, in side view, and Fig. 2 is a detail of the holder partly in longitudinal section and having a borer inserted therein. Fig. 3 is a section on the line III—III and Fig. 4 is a section on the line IV—IV in Fig. 2.

Referring to Fig. 1, 1 is the frame of the striking tool, containing an electric motor 2 which rotates a sleeve 3. Mounted to slide in this sleeve 3 is a striking body 4 receiving a reciprocating motion by the action partly of the shock of the striking body 4 against the anvil 5, partly by an energy storer or the like, for instance balls 6 acted upon by the centrifugal force. Inserted into the anvil 5 is a tool-holder 7, the downward motion of the same being limited by the bows 8 mounted at the bottom end of the frame, the outer

ends of the bows engaging a flange 9 located at the holder.

Finally, the very tool—in the example chosen a borer having a cross-shaped section—is inserted into the holder. In order to hold this borer so as to prevent it from being thrown out away from the holder, when the anvil is exposed to the influence of the striking body without the end of the borer 12 bearing on this occasion simultaneously against any support, the holder has its fore end provided with a sleeve 11 of rubber or similar resilient matter pushed on the flange 10. The channel made in this sleeve 11 to allow the borer 12 to be inserted into the holder is, according to the present invention, given a cross-section similar to, but somewhat less than the cross-section of the shaft of the borer. By this fact the borer is rigidly secured in the sleeve by friction caused by the sleeve pressing by its own elasticity against the tool shaft.

The invention may be applied to all shapes of cross-sections of the tool or tool-shaft, for instance a circular or a square one. The shape of cross-section of the tool or tool-shaft shown in the drawings is only an embodiment. The manner in which the resilient portion of the holder is fixed to the other part of the holder may, of course, also be varied in many ways without departing from the principle of the invention.

Having now particularly described the nature of our invention and the manner of its operation, what we claim is:

Tool holder for motor-driven striking tools, comprising a main tool holder member, provided with a flange at its forward end, an additional holder member made of a resilient material, this additional member being provided at its rear end with a flange corresponding to the flange of the main holder member and adapted for fixing the resilient part to the forward end of the main tool holder; the main tool holder and the resili-

ent member each being provided with a channel with a constant cross section, which concerning the main tool holder is of the same size as the cross section of the tool shaft but concerning the resilient member is somewhat less than the said cross-section, whereby when the tool shaft is pushed into the tool holder, the resilient member holds the said shaft in its position by friction arising from forces 10 acting at right angles against the axis of the shaft.

In testimony whereof we affix our signatures.
